UNITED STATES PATENT OFFICE

97,119

DESIGN FOR A CUP

R. Guy Cowan, Syracuse, N. Y., assignor to Onondaga Pottery Company, Syracuse, N. Y., a corporation of New York

Application January 28, 1935, Serial No. 55,115

Term of patent 14 years

To all whom it may concern:

Be it known that I, R. Guy Cowan, a citizen of the United States, residing at Syracuse, in the county of Onondaga and State of New York, and having his post-office address at 220 Sedgewick Street, Syracuse, New York, have invented a new, original, and ornamental Design for a Cup, of which the following is a specification, reference being had to the accompanying drawing, forming part thereof.

In the drawing, the figure is an elevational view of the cup, showing my design.

The dominant feature of the invention resides in the ornamentation at the upper edge of the cup.

The cup shown is of conventional circular contour.

I claim:

The ornamental design for a cup substantially as shown and described.

In testimony whereof, I have hereunto signed my name, at Syracuse, in the county of Onondaga and State of New York, this 25th day of January, 1935.

R. GUY COWAN.
